UNITED STATES PATENT OFFICE.

JAMES H. PAIGE, OF MANCHESTER, NEW HAMPSHIRE.

COVER FOR PRESERVING JARS.

1,425,212.

Specification of Letters Patent. Patented Aug. 8, 1922.

Application filed August 25, 1920. Serial No. 406,018.

To all whom it may concern:

Be it known that I, JAMES H. PAIGE, a citizen of the United States, residing at Manchester, in the county of Hillsborough and State of New Hampshire, have invented 5 certain new and useful Improvements in Covers for Preserving Jars, of which the following is a specification.

Glass covers for glass fruit jars as at 10 present furnished to the trade have several defects. Glass jars and covers are molded and as accuracy is impossible, allowance as to dimensions is made, for otherwise many of such covers would not fit the jar. This 15 necessary "oversize" results in many of the covers being so loose on the mouth of the jar that they can shift laterally across the mouth until the inner or upright wall of the cover strikes the extreme upper part of 20 the jar around which the usual rubber gasket is placed.

Consequently the ordinary glass cover for 25 a fruit jar permits the gasket to distort or "squash" so that imperfect or unsatisfactory sealing results. The ordinary cover also requires much patience and great effort to effect its removal, after sealing, and the unsealing frequently results in chipping, splitting, splintering or cracking of the cover 30 and mouth of the jar, which destroys their usefulness and also may necessitate the loss of the contents of the jar.

My object is to overcome the foregoing 35 and other defects inhering in preserving jar covers as at present known to the art.

My improvements comprise an inner annular ridge adapted to rest upon and seal the gasket, and an outer marginal part or edge on the cover which may be either annular or provided with notched portions, 40 located in a plane below the inner annular ridge and arranged to overhang the mouth of the jar. The sealing is effected entirely by the inner annular ridge; the overhanging, lower peripheral part of the cover serves as an abutment to prevent lateral displacement of the cover and gasket and hence 45 does away entirely with the "squashing" action hereinbefore referred to. Furthermore, the outer or peripheral portion of the cover 50 enables the latter to be easily loosened from a jar which has been sealed and entirely obviates all danger of cracking, splintering, chipping or otherwise injuring either the 55 jar or the cover.

A modification of the cover wherein parts

of the peripheral portion are omitted, enables the person sealing the jar to engage her thumb with the wire, binding lever or the like, when pressing the same downwardly in 60 the operation of sealing.

My invention has the further advantage that inasmuch as lateral displacement of the rubber gasket is prevented by reason of the improved form of the cover, there may be 65 used a narrower gasket than is at present employed, thus lessening the expense for gaskets.

The invention is susceptible to modification and is not to be considered as limited 70 to the specific embodiments disclosed in the drawings and which are hereinafter described, so long as the essential principle is employed in whatever form the invention may assume.

In the accompanying drawings:—
Figure 1 is an elevation, partly in section;
Fig. 2 a bottom plan view of the cover;
Fig. 3 a top plan view of the jar;
Fig. 4 a top plan view of a modification; 80
and

Fig. 5 a side elevation thereof.

An ordinary jar, such as is commonly used for preserving, is shown at 1, the same being provided with a mouth 2 surrounded by 85 ledge or channel 3 for supporting the gasket 4.

My invention enables a gasket to be used 90 which is considerably narrower than the gasket commonly employed on preserving jars, thus saving in the aggregate considerable expense.

Any ordinary or preferred bail 5 and operating member 6 may be employed.

The cover 7 is provided with a ridge 8 95 with a central depression 9 of the usual form. On its under side the cover has an annular ridge 10 which is adapted to telescope over the mouth of the jar and to bear on the gasket. The outer edge or peripheral portion of the cover is in the form of a bead 11 which is located in a plane lower than that of the annular ridge or corrugation 10 and said bead is also located beyond the neck 100 of the jar. As a result of this construction there exists an annular space or groove 12 when the cover is in position and the jar is sealed, enabling a fork, knife or any ordinary culinary implement to be readily introduced for the purpose of releasing the cover 110 when the jar is to be opened. When the cover is locked in position the inner annular

ridge 10 presses firmly against the gasket 4 and the outer or peripheral bead 11 serves as an abutment for the gasket and thus prevents lateral shifting of the cover and hence 5 does away entirely with the distortion of the gasket and the "squashing" action hereinbefore referred to. The result is a perfect seal and yet the cover can be quickly and easily removed by merely introducing any 10 suitable implement such as a knife, fork, spoon or the like in the space 12 and by exerting a slight prying action.

Inasmuch as my invention does away with the distortion of the gasket due to the lateral shifting of the cover, a narrower gasket than those commonly employed, may be 15 used.

There being no distortion of the gasket and a free space 12 being provided, the 20 cover can be quickly removed without any danger of cracking, chipping, splintering, or breaking, either the jar or the cover.

Referring now to Figs. 4 and 5 the construction and action are identical with the 25 foregoing disclosures, except that portions of the edge of the cover are omitted by the provision of cut-outs or notches 12^a. These are preferably located at 90° apart; they 30 provide clearance for the thumb or thumb and forefinger in the manipulation of the bail 5 and operating member 6.

What I claim is:

1. The combination with a preserving jar having a mouth surrounded by a ledge or channel, and a gasket surrounding said 35 mouth and resting on top of said ledge, of a cover having an inner annular depending ridge whose crest is adapted to bear on the upper face of the gasket and is also provided with a distinct outer depending ridge, constituting the outermost edge of the cover, which is rounded and is separated from the inner ridge, said outer ridge serving as a 40 contact surface for the tool or device fulcrumed on the jar for the purpose of removing the cover.

2. A cover for preserving jars, provided with inner and outer ridges or corrugations depending from its lower surface, the inner ridge having a crest adapted to engage the upper face of the gasket of the jar, and the outer ridge constituting the outermost edge 50 of the cover and having a rounded part lying in a plane below that of the inner ridge 55 and serving as a guard for the inner sealing ridge and adapted for engagement by the tool or device fulcrumed on the jar for the purpose of removing the cover.

In testimony whereof I affix my signature. 60

JAMES H. PAIGE.
